C. B. FORWARD.

METHOD OF TREATING CRUDE OIL,
APPLICATION FILED SEPT. 8, 1914.

1,181,301.

Patented May 2, 1916.

Fig. 1.

UNITED STATES PATENT OFFICE.

CHAUNCEY B. FORWARD, OF URBANA, OHIO.

METHOD OF TREATING CRUDE OIL.

1,181,301.

Specification of Letters Patent. Patented May 2, 1916.

Application filed September 8, 1914. Serial No. 860,621.

To all whom it may concern:

Be it known that I, CHAUNCEY B. FORWARD, a citizen of the United States, residing at Urbana, in the county of Champaign 5 and State of Ohio, have invented certain new and useful Improvements in Methods of Treating Crude Oil, of which the following is a specification:

My invention has reference to an improvement 10 in the method of treating crude oil and the distillates thereof set forth particularly in my Letters Patent of the United States No. 1,088,693, and dated March 3, 1914. In my present invention, I have so far improved 15 on the method and apparatus set forth in said patent that the lighter distillates are delivered in a more purified state than formerly and there is a largely increased percentage in the volume of the 20 naphtha and gasoline series, as will presently be seen.

In the accompanying drawings, Figure 1 is an elevation lengthwise of my apparatus complete but showing the retort in longitudinal section elevation. Fig. 2 is an elevation in section enlarged, of one of the intermediate condensers which is individual and different from the others as hereinafter described.

30 By the means thus shown, I am enabled to purify the fractional distillates obtained from those portions of crude oil from which the heavier fractions of oils have been previously condensed as shown substantially in 35 my said Patent No. 1,088,693, as well as to obtain a materially increased percentage of the more volatile or lighter products as above described. In my said Patent No. 1,088,693, I state that the several condensers may be 40 changed in size and numbers, and made smaller or larger here and there in the series according to the character of the crude oil being handled at the time and the number and character of the fractions desired there- 45 from, and some of these possibilities and changes structurally are present in this case, plus the changes necessary to secure the results herein described. Thus, the drawings show a retort R and a series of condensers 50 D, E, F, G, H, I, and K, and a condenser worm L connected and operating in the order named. Discharge is from the top of one condenser to the bottom of the next in order, as formerly, by a pipe 2, and a drain 55 3 for the condensed products from each by the trap or outlet 4. Formerly, the opera-

tion was progressive and similar in manner from one condenser to the other, the initial pressure from or through the retort being exclusively relied upon to drive the fluid 60 vapors through the series of condensers to the worm L and leaving the condensations in each according to the size and position of the columns. Of course, the successive condensations passed off through the successive 65 traps or outlets 4 and they do so in this case, but I have found it desirable for commercial reasons to add a further treatment to the lighter distillates after the heavy oil vapors have been condensed. Hence, I have provided a condenser column G in the series with a superheated steam jacket J about said column and introduce a superheated steam jet 6 into the entrance or neck at the bottom of said column. The superheated steam to 70 both the said jacket and the jet is shown in this instance as coming from the steam pipe 7, and will be at about the same temperature as the retort, say 650° F. less the comparatively slight loss by radiation *en 80 route*, but as shown in Fig. 1 the pipe 7 is connected by a pipe 7' to the cylinder C located within the retort R, the cylinder C being supplied with steam through pipe D'. The steam may be taken from any other avail- 85 able source. The effect of said jet on the oil vapors at this point is to break them up into still more minute particles and assist in the reheating of the same in connection with the superheated steam about said condenser 90 column G. The result of this operation is the purification of the distillates and at the same time, an increased percentage of volatile oils condensed with the naphtha and gasoline. This increase, however, in the 95 naphtha and gasoline, is secured at a cost of a reduction in the amount of heavier oils, the vapors of which have been treated by the above improved method. By reason of the action of the steam jacket and jet on the 100 vapors in condenser G, there will be very little condensation therein, and it will be observed that the bottom of the said column is constructed so as to catch whatever condensation does occur and trap the same off from the opening to the side of the center hole instead of from the central opening as is the case in the other condenser columns; a pipe 10 connects with said bottom and has the usual trap or outlet 4.

On account of the increased temperature of the vapors as they come from condenser

G by reason of the steam jacket J and the injection of steam therein, it is necessary to make the condenser H relatively larger so as to secure the condensation of the desired amount of the distillate that the operator wishes to obtain at this point in the operation. If, say, Ohio crude oil were being handled, the distillates coming from both the jacketed condenser G and the condenser H would be what is known as intermediate gas or fuel oil. Although the quantity of this distillate is less than is secured by the apparatus shown in my Patent No. 1,088,693 of March 3, 1914, the reason for the increased condensing area required at this point, as shown in this improved apparatus over said patent, is because of the increase in the temperature of the vapors in condenser column G, necessitating the larger condensing surface to secure the desired amount of condensation of the required gravity of distillate. The condenser I is relatively smaller by reason of the decreased amount of kerosene secured by this improved method while condenser K is correspondingly larger by reason of the increased amount of naphtha obtained as well as condenser L for the gasoline.

I have shown the middle condenser in the series of seven with superheating means for the vapors which are uncondensed at that point in the process, but for that matter, it might be one or another of the said condensers and the degree of heat may be varied according to the results desired. So also may the individual condensers be varied as to elevation or length, it being understood that all are built in sections and adapted to be used as described and claimed in my patent above recited.

As the oils from the different oil fields are all different in character, it is obvious that it would be necessary for one to be

skilled in the art in order to know at which point to place the steam jacket condenser as well as to determine the size and number of condensers to be used according to the oil being treated and the number of fractions desired in each case.

When starting operations all the valves ⁵⁰ *v* from the outlets or traps from the several condensers are closed and are kept closed until the said traps or goose necks ⁵⁵ *u* are filled and then they are opened. This avoids the possible blowing out of uncondensed vapors in the several condensers until said traps are filled and it also helps to equalize the pressure throughout the series. It will be seen that the final condenser or worm L has a valve or cock ⁶⁰ *v* the same as those preceding. After all the valves are opened there will be a sustained flow from the several condensers according to their respective gravities and condensation and discharge are continued without cessation ⁶⁵ throughout the period of operation.

What I claim is:

The process herein described of treating hydro-carbon oils, which consists in passing the vapors from a still through a series ⁷⁰ of successively connected vaporating condensers in all of which the vapors are alike exposed, and after the vapors have passed through a plurality of the condensers reheating the vapors in one of the condensers ⁷⁵ before they enter the remaining condensers to a temperature in excess of the last condenser through which they passed before entering the reheat.

In testimony whereof I affix my signature ⁸⁰ in presence of two witnesses.

CHAUNCEY B. FORWARD.
